UNITED STATES PATENT OFFICE.

WILLIAM M. SMITH, OF WEST MERIDEN, CONNECTICUT, ASSIGNOR TO THE MERIDEN BRITANNIA COMPANY, OF SAME PLACE.

DESIGN FOR COFFIN-SCREWS.

SPECIFICATION forming part of Design No. 11,765, dated May 4, 1880.

Application filed April 2, 1880. Term of patent 7 years.

To all whom it may concern:

Be it known that I, W.M. M. SMITH, of West Meriden, in the county of New Haven and State of Connecticut, have invented a new Design for 5 Coffin-Screws; and I do hereby declare the following, when taken in connection with the accompanying drawings and the letters of reference marked thereon, to be a full, clear, and exact description of the same, and which said 10 drawings constitute part of this specification, and represent, in—
Figure 1, a side view; Fig. 2, a top view of the plate.
This invention relates to a design for an ornamental screw-head, such as used for coffins and like purposes, commonly called "coffin-screws;" and the design consists in the representation of a rose-bud lying on the plate which forms the bearing for the screw-head.

20 A is the plate or base, which consists of a floriated sprig with the representation of a

band diagonally around it, as seen in Fig. 2. B is the screw-head, representing a rose-bud as lying on said plate, the screw extending from the under side of the bud through the plate. 25

The screw-head may be used with a different plate, or a different head may be used with this plate. The design is therefore not to be understood as for the combination of the head and plate shown. 30

I claim—

1. The design for coffin-screw head, consisting of the representation of a rose-bud lying upon its side, as shown in the accompanying illustration.
2. The design for coffin-screw plate, consisting of the floriated sprig with diagonal band, as shown in the accompanying illustration.

WILLIAM M. SMITH.
